The ornamental design for a vascular model, as shown and described.

DESCRIPTION

FIG. 1 is a front view of a vascular model showing our new design;

FIG. 2 is a top plan view thereof;

FIG. 3 is a bottom plan view thereof;

FIG. 4 is a left side view thereof;

FIG. 5 is a right side view thereof;

FIG. 6 is a cross sectional slice, taken along line 6-6 of FIG. 1;

FIG. 7 is a cross sectional slice, taken along line 7-7 of FIG. 1;

FIG. 8 is a cross sectional slice, taken along line 8-8 of FIG. 1;

FIG. 9 is a cross sectional slice, taken along line 9-9 of FIG. 1; and,

FIG. 10 is a cross sectional slice taken along line 10-10 of FIG. 1.

The rear view is omitted, because it is a mirror image of the front view. The shading on the figures indicates transparency.
